BY

Fred C. Matheny
ATTORNEY

UNITED STATES PATENT OFFICE.

WILLIAM STERN, OF SEATTLE, WASHINGTON.

DESIGN FOR A CHARM.

Application filed April 12, 1923. Serial No. 5,789. Term of patent 7 years.

To all whom it may concern:-

Be it known that I, WILLIAM STERN, a citizen of the United States, residing at Seattle, in the county of King and State of Washington, have invented a new, original, and ornamental Design for a Charm, of which the following is a specification, reference being had to the accompanying drawings, forming a part thereof.

In the drawings Figure 1, is a front elevation showing the front side of a charm in accordance with my invention.

Fig. 2, is an edge view of the same.

Reading from right to left the characters on the charm represent the Jewish letters

"mem" "zion" and "lamed," respectively which, taken collectively in the order named form the Jewish word pronounced, *masl*, which, translated into English means "luck." In addition, the three Jewish letters "lamed" "zion" and "mem" are intended as abbreviations of the three Jewish words "loshen" "zman" and "mokem," which, translated, mean respectively, knowledge, time, and place.

I claim:

The ornamental design for a charm, as shown.

WILLIAM STERN.
